By Clarence A. O'Brien, Attorney

UNITED STATES PATENT OFFICE

SAM STENSON BRAME, OF WACO, TEXAS

EXERCISING DEVICE

Application filed March 23, 1928, Serial No. 264,237. Renewed March 1, 1930.

The present invention relates to improvements in exercising devices and has for its principal object to provide a device that can be readily and easily attached to a door frame, or supported between a pair of stationary spaced uprights, the device including a swinging frame having a horizontal bar by which a person may carry out the exercises.

One of the important objects of the present invention is to provide an exercising device of the above mentioned character wherein means is provided for detachably securing the swinging frame in a suitable support whereby said frame is capable of vertical swinging movement, additional means being provided for locking the free end of the frame against swinging movement when the device is not in use.

A further object is to provide a device of the above mentioned character which is simple in construction, inexpensive, strong and durable and further well adapted to the purpose for which it is designed.

Other objects and advantages of the invention will become apparent from the following description when taken in connection with the accompanying drawings.

In the accompanying drawings wherein like reference characters indicate corresponding parts throughout the several views:

Figure 1 is a side elevation of the exercising device embodying my invention showing the manner in which the same is secured in a door frame.

Figure 2 is a vertical sectional view taken approximately on the line 2—2 of Figure 1.

Figure 3 is a similar section showing the manner in which the swinging frame is actuated when a person uses the device.

Figure 4 is a detail sectional view showing the manner in which one end of the horizontal hand bar is secured in the adjacent standard of the swinging frame.

Figure 5 is a fragmentary side elevation of one of the standards of the swinging frame and the spring catch associated with one of the openings to receive one end of one of the horizontal cross bars, and

Figure 6 is a fragmentary sectional view

showing the manner in which the supporting bar for the swinging frame is positioned between the brackets secured to the opposite side faces of the door frame.

In the drawings wherein for the purpose of illustration is shown the preferred embodiment of my invention, the numeral 1 designates generally a door frame of any conventional construction, the vertically swinging door that is associated therewith being shown at 2. Secured on the inner opposed faces of the door frame at vertically spaced intervals are the complementary brackets 3 and 4, respectively, the same being arranged in opposed pairs and as is more clearly disclosed in Figure 3 of the drawings, each of the brackets 3 is of greater thickness than the opposite brackets 4. Each of these brackets is preferably in the form of a rectangular metallic plate that is formed at its respective corners to suitable openings to receive fastening screws or the like that are driven into the sides of the door frame. Furthermore, each bracket is formed with a central transverse socket, the socket being formed in each of the brackets 3 being designated by the numeral 5, while the socket formed in each of the opposed brackets 4 is illustrated at 6, and particular attention to this feature is directed to Figure 6 of the drawing.

An upper cross bar or rod 7 which is of a length less than the width of the door frame has arranged on each end thereof, a metallic cap or ferrule 8. One end of this cross rod 7 is formed with a transverse pocket 9 to receive the cross piece 10 that is arranged in the inner end of the socket 6 formed in the uppermost one of the brackets 4.

The other end of this cross rod or bar 7 is formed with an inwardly extending pocket in which is arranged a coil spring 11, the inner end of said spring engaging with the innermost end of the pocket while the outer end of said spring is in engagement with the inner end of a sliding plunger 12, the outer end of which projects beyond the adjacent end of the cross rod and is rounded. The spring 11 normally urges this sliding plunger outwardly so that the outer end will engage with the in-

nermost end of the socket 5 formed in the uppermost bracket 3 in the manner as shown in Figure 6 whereby said upper cross rod or bar is positively secured between the uppermost pair of opposed brackets.

Similar cross rods 13 are supported between the lowermost pair of opposed brackets to form foot engaging rails. An additional similar constructed cross bar 14 is 10 removably supported between an intermediate pair of opposed brackets for a purpose hereinafter to be more fully described.

The exercising device further includes the provision of a vertically swinging frame designated generally by the numeral 15 and this frame includes a pair of wooden side bars or standards 16 that are secured together in spaced relation by the cross rods 17 and detachable horizontal bars 18, the construction 20 of which will be presently described. The upper ends of the side bars or standards of the swinging frame 15 are formed with registering openings to accommodate the supporting bar 7 which has its ends supported in the sockets 5 and 6 of the uppermost brackets 3 and 4 respectively. Each of the side bars or standards is formed with a series of spaced circular openings 19, the openings in one side bar or standard registering with the 30 openings in the other side bar or standard for accommodating one or more of the horizontally extending handle bars 18, the outer ends of the handle bars being provided with metal caps or ferrules such as are shown at 35 20 with reference more particularly to Figure 4.

For the purpose of securing each of the handle bars against displacement from the respective registering openings provided therefor in the side bars or standards of the swinging frame, there is arranged on one side edge of each standard adjacent each of the circular openings 19, a spring strip 21 that is secured at one end as at 22, the free 45 end carrying an inwardly extending pin 23 that projects through the inwardly extending aperture formed in the standard and the free end of this pin enters the circular opening as clearly shown in Figure 5.

The outer ends of each handle bar are formed with annular channels, and the adjacent portions of the metallic caps or ferrules are pressed inwardly and the inner ends of the spring pressed pins engage in these channels 24 to prevent sliding movement of the handle bars after the same have been properly positioned in the aligned openings provided therefor in the respective standards or side bars of the swinging frame 15. The free 50 ends of the spring strips provide finger pieces whereby the same may be manually engaged and moved outwardly whereby to disengage the pins from the annular channel in order to facilitate the removal of the handle bar from 60 the frame whenever desired.

In use, the door 2 is swung to an open position, and a person grasps the handle bar 18 to swing the frame 15 vertically, and the user of the device may place his feet upon one of the foot rails 13 as indicated in Figure 3 of the drawings. When not in use, the frame 15 is locked in a vertical position within the door frame against swinging movement by positioning the locking bar 14 in a predetermined pair of opposed brackets secured to the inner opposed faces of the door frame, and the lower free ends of the side bars or standards 16 are notched as illustrated at 70 25 for engagement with this locking bar 14 as clearly shown in Figure 2. It is of course understood that this locking bar 14 is removed from between the door frame when the swinging frame 15 is to be used.

While I have shown the exercising device as being mounted in a door frame, the same 80 can be arranged in a pocket formed in the wall or may furthermore be supported between a pair of uprights secured on a stand or the like.

The simplicity of my improved exercising device enables the parts to be readily and easily set up in position for use, and the cross bars that extend between the sides of the door frame can be quickly and easily inserted or removed from their respective brackets.

An exercising device of the above mentioned character will furthermore be strong and durable, and will also afford a simple and efficient means whereby a person may exercise whenever desired.

While I have shown the preferred embodiment of my invention it is to be understood that minor changes may be made in the invention in the size, shape and arrangement of parts without departing from the spirit of the invention and the scope of the appended claims.

Having thus described the invention, what I claim as new is:—

1. In an exercising device of the class described, the combination with a door frame, socket members secured to the inner opposed faces of the door frame and arranged in pairs, a cross bar detachably secured at its ends in one pair of sockets in the upper portion of the door frame, a vertically swinging frame supported at its upper end on the said cross bar, a handle bar carried by the lower portion of said vertically swinging frame, and means for locking said frame in a vertical position in the door frame against swinging movement.

2. In an exercising device of the class described, the combination with a door frame, socket members secured to the inner opposed faces of the door frame and arranged in pairs, a cross bar detachably secured at its ends in one pair of sockets in the upper portion of the door frame, a vertically swinging frame supported at its upper end on the said cross bar, a

handle bar carried by the lower portion of said vertically swinging frame, means for locking said frame in a vertical position in the door frame against swinging movement, 5 said last mentioned means comprising an additional cross rod for disposition between a pair of socket members located adjacent the lower portion of said vertically swinging frame, said lower portion of the vertically 10 swinging frame being notched for engagement with said last mentioned cross bar.

3. In an exercising device of the class described, the combination with a door frame, socket members secured to the inner opposed 15 faces of the door frame and arranged in pairs, a cross bar detachably secured at its ends in one pair of sockets in the upper portion of the door frame, a vertically swinging frame supported at its upper end on the said cross bar, a handle bar carried by the lower portion of said vertically swinging frame, means for locking said frame in a vertical position in the door frame against swinging movement, 20 said last mentioned means comprising an additional cross rod for disposition between a pair of socket members located adjacent the lower portion of said vertically swinging frame, said lower portion of the vertically 25 swinging frame being notched for engagement with said last mentioned cross bar, and a foot rail supported between an additional pair of socket members adjacent the lower portion of the door frame.

4. In an exercising device, the combination 30 with a pair of spaced uprights, socket members secured on the inner opposed faces of the uprights and arranged in pairs, a cross rod detachably supported between the uprights in the uppermost pair of socket members, a 35 frame for vertical swinging movement between the uprights, said frame including a pair of interconnected standards mounted at their upper ends on said cross bar, a handle bar detachably secured between the lower 40 ends of the standards, and means for locking said frame in a vertical position between the uprights against swinging movement.

5. In an exercising device, the combination 45 with a pair of spaced uprights, socket members secured on the inner opposed faces of the uprights and arranged in pairs, a cross rod detachably supported between the uprights in the uppermost pair of socket members, a 50 frame for vertical swinging movement between the uprights, said frame including a pair of interconnected standards mounted at their upper ends on said cross bar, a handle bar detachably secured between the lower 55 ends of the standards, means for locking said frame in a vertical position between the uprights against swinging movement, said last 60 mentioned means comprising a locking rod detachably supported between an additional pair of socket members located adjacent the 65 lower ends of the standards, said lower ends of

the standards being notched for engagement with the locking cross bar.

6. In an exercising device, the combination 70 with a pair of spaced uprights, socket members secured on the inner opposed faces of the uprights and arranged in pairs, a cross rod detachably supported between the uprights in the uppermost pair of socket members, a frame for vertical swinging movement between the uprights, said frame including a 75 pair of interconnected standards mounted at their upper ends on said cross bar, a handle bar detachably secured between the lower ends of the standards, each end of the handle bar being formed with an annular channel, 80 each of the standards being formed with a transverse opening to receive the adjacent channeled end of the handle bar, and a spring pressed pin extending through each standard for engagement within the channel to secure 85 the handle bar against sliding movement with respect to the standard.

7. In an exercising device, the combination 90 with a pair of spaced uprights, socket members secured on the inner opposed faces of the uprights and arranged in pairs, a cross rod detachably supported between the uprights in the uppermost pair of socket members, a frame for vertical swinging movement between the uprights, said frame including a 95 pair of interconnected standards mounted at their upper ends on said cross bar, a handle bar detachably secured between the lower ends of the standards, each end of the handle bar being formed with an annular channel, each 100 of the standards being formed with a transverse opening to receive the adjacent channeled end of the handle bar, a spring pressed pin extending through each standard for engagement within the channel to secure the handle bar against sliding movement with respect to the standard, the lower ends of the standards being notched, and a locking bar 105 detachably supported between a pair of socket members adjacent the notched ends of the standards, said notched ends being adapted to engage with the locking bar.

In testimony whereof I affix my signature.
SAM STENSON BRAME.
